UNITED STATES PATENT OFFICE

2,600,553

COLLAPSIBLE TUBE HOLDER WITH TUBE-
WINDING SPOOL

William T. Lord, Freeport, N.Y.

Application October 4, 1949, Serial No. 119,473

2 Claims. (Cl. 222—100)

1

This invention relates to collapsible tube holders, and more particularly to a holder removably attachable to a wall for supporting a collapsible tube, such as a toothpaste tube, in position for use.

It is among the objects of the invention to provide an improved collapsible tube holder of simplified construction which can be mounted on and removed from a wall, at will, and will receive and firmly support a collapsible paste or cream tube in position for dispensing the tube contents therefrom, which can be economically manufactured from readily-available, resilient materials and will resiliently engage a tube neck to facilitate mounting the tube therein, which includes manually-operative means engageable with the tube for progressively dispensing the tube contents, and is especially designed for the easy removal of an exhausted tube and replacement of a new tube therein, and which is durable in construction, highly sanitary, and neat and attractive in appearance.

Other objects and advantages will become apparent from a consideration of the following description and the appended claims in conjunction with the accompanying drawing, wherein:

Figure 1 is a front elevation of a tube holder, illustrative of the invention, portions being broken away and shown in cross-section to better illustrate the construction thereof;

Figure 2 is a longitudinal cross-section on the line 2—2 of Figure 1; and

Figure 3 is a bottom plan view of the tube holder illustrated in Figure 1.

With continued reference to the drawing, the tube comprises an elongated, rectangular receptacle 10 of a size and shape to loosely receive therein a conventional collapsible tube 11. This receptacle is formed of thin-walled, resilient material, a molded synthetic resin material being preferred and may be provided in various colors and with surface ornamentation, as may be desired. Two elongated slots 12 are provided, respectively, in the opposite side walls of the rectangular receptacle with each slot extending longitudinally of the corresponding side wall substantially along the mid-width location of the side wall and from a location near one end to a location near the opposite end of the side wall, and an enlarged, rectangular opening 13 is provided in the back wall of the receptacle. At each end of the opening 13 the back wall is provided with rounded notches 14 and 15 and the flanged or button portions of two rubber suction cups 16 and 17 are engaged, respectively, in these notches

2

for attaching the suction cups to the receptacle at respectively-opposite ends of the opening in the back wall of the receptacle. These suction cups are engageable with a smooth wall surface, such as the tiled wall of a bathroom, to detachably secure the collapsible tube holder to the wall in proper position for use of the contents of the tube.

The receptacle 10 is open at one end and a flanged cover 18 is provided to fit upon the receptacle at its open end, this cover being removable for placing a tube in the receptacle.

At its opposite end the receptacle is provided with a pyramidal formation 19 having an apical opening 20 of a size to receive the screw-threaded neck 21 of the tube, as is clearly illustrated in Figure 2. This formation 19 comprises four thin-walled, resilient prongs, each of which extends from a respective side wall of the receptacle 10 to the apical opening 20 to resiliently grip the neck of a tube forced through the opening 20 from within the receptacle. A tube roller 22 is inserted through the slots 12 and extends transversely of the receptacle 10. This roller comprises an elongated, cylindrical body bifurcated to provide a slot 23 extending from one end to a location adjacent the opposite end of the body. A thumb-knob 24 is provided on one end of the cylindrical body and the body is externally screw-threaded at its opposite end, as indicated at 25, and receives a hollow, internally screw-threaded cap 26 which is similar in external size to the knob 24 and provides a thumb-knob at the corresponding end of the roller. The slot 23 of the bifurcated roller receives a collapsible tube near the flattened, closed end of the tube, the furcations of the roller being firmly engaged with the tube by threading the cap 26 onto the screw-threaded end of the roller.

In order to mount a tube in the holder, the closure cap provided on the tube is removed and the screw-threaded neck of the tube is forced through the opening 20 in the bottom end of the holder, so that the ends of the prong at the opening 20 will engage in the threads on the neck of the tube. The ends of the prong at the opening 20 are preferably beveled, as indicated at 27, to provide thread-engaging edges on these prongs. After the neck of the tube is secured in the opening 20, the roller 22 is inserted through the slots 12 in straddling relationship to the flattened end portion of the tube and the cap 26 is threaded onto the screw-threaded end of the roller. The cover 18 is then placed in position on the upper end of the receptacle and the receptacle is mounted on

the wall at a convenient location by the suction cups 16 and 17.

For dispensing the contents of the tube, a toothbrush, as indicated at 28, in Figure 2, is held directly below the neck of the tube and the roller 22 is turned until the desired amount of paste has been forced out of the tube and onto the toothbrush. When a sufficient quantity of toothpaste has been dispensed, turning of the roller 22 is discontinued, and the consistency of the toothpaste will then preclude any further movement of the paste out of the tube or any drip of its contents from the tube, when the device is not in use.

When it is desired to remove an exhausted tube, the roller is first unwound from the tube, the cap 26 is then removed and the roller withdrawn from the receptacle. With the receptacle removed from the wall, two or more fingers are then inserted through the opening 13 and the tube is rotated in the receptacle until its neck threads out of the opening 20 in the bottom end formation of the holder, after which the exhausted tube is removed through the open, upper end of the receptacle, and a new tube placed in the receptacle in the manner indicated above.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A collapsible tube holder comprising, a hollow, thin-walled receptacle of resilient material having a pair of oppositely-disposed, longitudinal slots therein and a large opening between said slots, said receptacle having an open end and having at its opposite end an outwardly projecting formation provided with an apical opening and comprising separate, resilient prongs extending from the wall of said receptacle to said

opening to resiliently grip a collapsible tube neck forced through said opening from within said receptacle, a tube-winding spool comprising a bifurcated member inserted through said slots for receiving a collapsible tube near its closed end between the furcations of such member and winding the tube to dispense the contents thereof, two suction cups of flexible material secured to said receptacle at respectively-opposite ends of said opening, and a removable cover closing the open end of said receptacle.

2. A collapsible tube holder comprising an elongated, rectangular receptacle of thin-walled, resilient material having elongated slots respectively-extending longitudinally of two opposite side walls along the mid-width location of said side walls and between locations near the opposite ends of such walls and having a large opening in its back wall, said receptacle having one end open and having at its opposite end a pyramidal formation provided with an apical opening and comprising four separate, resilient prongs extending respectively from the walls of said receptacle to said apical opening to resiliently receive and grip a collapsible tube neck forced through said tube opening from within said receptacle, a tube-winding spool comprising a bifurcated member inserted through said slots for receiving a collapsible tube near its closed end between the furcations of such member and winding the tube to dispense the contents thereof, two suction cups of flexible material secured to said receptacle at opposite ends of the opening in said black wall, and a removable cover closing 35 to open end of said receptacle.
